UNITED STATES PATENT OFFICE

2,505,416

SAFETY STOP FOR AWNINGS

Eugene Mahaffey, Memphis, Tenn.

Application August 24, 1946, Serial No. 692,805

2 Claims. (Cl. 160—66)

1

My invention relates to improvements in safety stops for awnings, the primary object in view being to provide a substantially enclosed stop in the operating mechanism for the raising and lowering roller of awnings, and which is adapted to prevent lowering of the awning sheet past a predetermined position beyond which damage might result to the awning structure and an unsightly appearance be presented by the awning, and whereby the stop is protected against damage from rain, dust, and the like.

Another object is to provide a device of the character and for the purpose set forth which is adapted to be incorporated in present-day awning structures without necessitating appreciable alteration in such structures, is inexpensive to manufacture, and not liable to get out of order.

To the accomplishment of the above, and subordinate objects presently appearing, a preferred embodiment of my invention has been illustrated in the accompanying drawing, set forth in detail in the succeeding description, and defined in the claims appended hereto.

In said drawings—

Figure 1 is a view in side elevation illustrating my improved safety lock applied.

Figure 2 is a view partly in front elevation and partly in longitudinal section of the safety lock detached and drawn to a larger scale.

Figure 3 is a view in transverse section taken on the line 3—3 of Figure 2.

Referring to the drawing by numerals, my improved safety stop has been shown therein, for illustrative purposes, as embodied in a well-known type of awning in which the sheet 1 is adapted to be wound upon and unwound from a roller shown in dotted lines at 2 with end studs, as at 3, journaled in bearing brackets, as at 4, fixed to the building wall 5 by upper and lower bolts 6, 7. The bearing bracket 4 as shown has the form of a gear casing housing a worm gear drive, not shown, for the stud 3 journaled in the bracket. Such a worm drive is shown in U. S. patent to E. F. Barber, No. 1,688,776, dated October 23, 1948, to which attention is invited. The sheet 1 is connected at its lower edge to the usual awning frame 8 having rear ends pivoted, as at 9, for vertical swinging of said frame on sleeves, as at 10, vertically slidably upon guide rods, one of which is shown at 11, bolted, as at 12, to the wall 5. The numeral 12 designates the usual frame hold-down rod 13 pivoted, as at 14, on the wall 5 and pivotally and slidably connected, as at 15, to the awning frame 8, in a manner and for a purpose which will be understood.

2

According to my invention, a tubular guide sleeve 16 of rectangular cross-section is suspended by an upper end thereof, as presently described, from the bearing bracket 4 in upright position and directly beneath said bearing bracket. For suspending the guide sleeve 16, an upper end lip 17 is provided on one side thereof with bolt holes 18 therein for receiving the lower bolts 7, whereby said lip 17 is clamped to said bearing bracket.

A threaded shaft 19 extends through the guide sleeve 16 with an enlarged upper end head 20 adapted to substantially close the upper end of said sleeve, and from which a short, tubular socket 21 extends upwardly concentrically of said shaft and is provided with diametrically opposite bolt holes 22 therein. The socket 21 is sleeved over a stub shaft 23 depending from the bearing bracket 4 and operatively connected to the worm drive, not shown, in said bracket, for instance, as shown in the aforementioned patent to Barber. A bolt 24 passing through the bolt holes 22 and said stub shaft 23 secures the shaft 19 to the stub shaft 23 in pendant position. The shaft 19 is provided with a lower, reduced and squared end 25 having a transverse bolt hole 26 therein. A hook 27 with a socket end 28 sleeved over said end 25 is secured to the shaft 19 by a bolt 29 passing through said socket end 28 and the bolt hole 26. The hook 27 is designed for the coupling thereto of the usual awning operating crank shown in dotted lines at 29. A square nut 30 is provided on the shaft 19 and which slidably fits in said sleeve 16.

As will be manifest, the nut 30 is designed to be fed upwardly on the screw-shaft 19 in the guide sleeve 16 when said shaft is rotated in the proper direction to cause the roller 2 to unwind the sheet 1, and thus lower the awning, and when said sheet 1 is unwound to the proper extent, to abut the head 20 and stop further operation of said shaft 19 in the direction resulting in unwinding of said sheet 1. Thus, unwinding of the sheet 1 is limited in the properly lowered position of the same. By disconnecting the socket 21 from the stub shaft 23, and lowering said shaft 19 in said sleeve 16, the nut 30 may be set on said shaft 19 to predetermine the extent to which the sheet 1 may be unwound, after which the shaft 19 may be re-inserted in said sleeve 16 and said socket 21 re-connected to the stub shaft 23. To permit lowering of the screw-shaft 19, the head 20 thereof is of the proper size to slide in the guide sleeve 16.

The foregoing will, it is believed, suffice to

impart a clear understanding of my invention, without further explanation.

Manifestly, the invention, as described, is susceptible of modification without departing from the inventive concept, and right is herein reserved to such modifications as fall within the scope of the appended claims.

What I claim is:

1. A device of the class described for attachment to a stub shaft depending from a fixed housing of an awning roller drive, said device comprising a sleeve of right-angled form in cross-section attachable at one end to said housing to depend therefrom, a screw-shaft extending through said sleeve and having an enlarged upper end head attachable to said stub shaft and a lower hooked end attachable to a crank, and a square nut on said screw-shaft slidably fitting in said sleeve and feedable upwardly and downwardly on the screw-shaft upon rotation of said screw-shaft and movable into engagement with said head. 15

2. A device of the class described for attachment to a stub shaft depending from a fixed housing of an awning roller drive, said device comprising a sleeve of right-angled form in cross- 20

25

section, means for attaching said sleeve at one end to said housing to depend therefrom, a screw-shaft extending through said sleeve and having an enlarged upper end head, means for attaching said head to said stub shaft, a lower hooked end on said shaft attachable to a crank, and a square nut on said screw-shaft slidably fitting in said sleeve and feedable upwardly and downwardly on the screw-shaft upon rotation of said screw-shaft and movable into engagement with said head, said screw-shaft and nut being removable out of said sleeve for pre-setting of said nut into different starting positions thereon.

EUGENE MAHAFFEY.
